ABSTRACT

An adapter for connecting an electric cable to a blade-type fuse characteristic by an extruded metal body having at least one cable-receiving aperture with a set screw threadedly seated in the body and movable into the aperture, and a pressure bar for clamping the blade of a fuse in a tight-fitting surface-to-surface contact with the body.

CONNECTING ADAPTER FOR ELECTRIC CABLE AND FUSE

BACKGROUND OF THE INVENTION

1. Field of the Invention

This invention relates to an adapter for connecting one end of a blade-type fuse to an electric cable.

2. Description of the Prior Art

In the past, fusible switch equipment, such as panel-board switches, safety switches, and disconnect switches, have been provided with fuse jaws that have helper springs in order to obtain a reliable connection between the jaws and the blade of a blade-type fuse. To avoid overheating between the blade and the fuse jaws, helper springs are necessary to maintain pressure in the jaws to carry the current. As a result, there have been such widespread difficulties of inserting the blade between the fuse jaws, that is has often become necessary to drive the blades into the jaws with a mallet or other appropriate tool. One disadvantage of using such force for driving the fuse blade into place is that the jaws are mounted on insulating bases of resinous material which is readily breakable.

Associated with the foregoing have been problems of assembly and production costs of the switches having fuse jaws adapted to accept blade-type fuses.

SUMMARY OF THE INVENTION

It has been found in accordance with this invention that the foregoing problems may be overcome by providing an adapter for connecting one or more electric cables to a blade type fuse which adapter includes an extruded metallic body having first clamping means for holding one or more electric cables in electrical contact with the body, and having second clamping means for holding the blade of a blade-type fuse in contact with the body; the first clamping means comprising at least one cable-receiving aperture and a setscrew threadedly seated in the body and movable into the aperture for compressing the cable in place; and the second clamping means comprising a pressure bar with at least one bolt threadedly seated in the body for holding the bar in tight-fitting engagement with the blade of a fuse.

The advantage of the adapter is that it combines a fuse clamp and a wire or cable terminal into one extruded body and avoids an electrical joint and a source of heat. An ancillary advantage to the foregoing is a reduction in the number of parts otherwise required.

BRIEF DESCRIPTION OF THE DRAWINGS

FIG. 1 is a side elevational view, with parts broken away, of an electrical control structure comprising an enclosed fusible distribution switch and an improved adapter in accordance with the principles of this invention;

FIG. 2 is an enlarged end view of the adapter taken on the line II-II of FIG. 1;

FIG. 3 is an enlarged plan view of the adapter taken on the line III-III of FIG. 1;

FIG. 4 is an end view of another embodiment of the adapter; and

FIG. 5 is an end view of a second embodiment of the adapter.

DESCRIPTION OF THE PREFERRED EMBODIMENT

In FIG. 1, a fusible distribution panelboard switch structure is generally indicated at 10, and it includes a switch generally indicated at 12, a blade-type fuse 14, an adapter or connector 16, all of which are contained within a box or enclosure 18. The fusible distribution panelboard switch structure 10 may be used, for example, between one or more cables 20 and a bus bar (not shown) where the structure 10 is provided for branch switch use.

The switch 12 is of conventional structure having, among other things, a stationary contact 22, a movable contact 24, a switch handle 26, and a Z-type conductor bar 28. The switch 12 is manually operated from outside of the enclosure 18 by means of an external operating handle 30 which is rotatably mounted on a removable front panel 32 of the enclosure to operate an actuating member 34 that is mounted on the inner side of the front panel. The actuating member 34 operatively connects the external handle 30 with the switch handle 26.

The enclosure 18 is usually mounted on a panel-board (not shown) on the side opposite the front panel 32.

The blade-type fuse 14 includes blades 36 and 38 at opposite ends thereof, the former of which is attached or secured to the conductor bar 28 in a suitable manner such as a bolt-clamp 40. The blade 38 is connected to the adapter 16 in a manner specifically described below.

The adapter 16 is shown more particularly in FIGS. 2 and 3 and is adapted for providing a more suitable connection between the cable 20 and the blade 38 of a fuse 14 than has been available heretofore. The adapter 16 is composed of an electrically conductive material and is preferably a metal body such as an extrusion of aluminum or copper. As such, the adapter 16 is provided with a pair of similar spaced openings 42 and 44 as well as a clamping surface 46. The adapter may also be provided with an opening 48 in the center thereof for minimizing the weight of the adapter. The adapter 16 is preferably provided with a pair of spaced threaded openings 50 by which the adapter is secured in place within the enclosure 18. For that purpose, a pair of similar bolts 52 extend through a bottom panel of the enclosure 18, the inner surface of which is provided with a base 54 of electrically insulating material.

The openings 42 and 44 are generally circular or elliptical in transverse cross-section and are adapted to receive one or more cables 20. Each opening 42 and 44 is provided with a setscrew 56 which is seated in similar threaded openings 58. The openings 58 have axes which preferably extend through or intersect the longitudinal axes of the openings 42 and 44 so that when the setscrew 56 are tightened, the inner ends thereof clamp the cables 20 in place against the surface of the openings as shown in FIG. 2. Accordingly, the combination of each opening and said screw in the adapter 16 constitutes clamping means for holding an electric cable in electrical contact with the body of the adapter.

As shown more particularly in FIGS. 2 and 3, a pressure bar 60 is used in conjunction with the clamping surface 46. Each end of the bar 60 is apertured to receive a tightening bolt 62 for applying pressure to the blade 38 of the fuse 14. Each bolt 62 is seated in a

threaded opening 64 in the adapter. Thus, the combination of the clamping surface 46, the pressure bar 60, and the bolts 62 constitutes clamping means for holding the fuse blade 38 in contact with the adapter 16. Inasmuch as the adapter 16 is an integral metal body composed of a metal, such as aluminum or copper, a highly conductive current path is provided between the cables 20 and the blade 38 of the fuse 14.

As shown in FIG. 3, the clamping bar 60 is spaced longitudinally along the axis of the openings 42 and 44 from the setscrews 56.

Another embodiment of the invention is shown in FIG. 4 wherein an adapter 66 is provided with a single opening 68 for receiving the cable 20. The body of the adapter 66, through which the opening 68 extends, includes a pair of flanges 70 and 72, the former of which provides a clamping surface 74 and the latter of which is provided with similar spaced threaded openings 76 in a manner similar to the openings 50 of the adapter 16. In other respects, the adapter 66 is similar to the adapter 16 in that it is provided with a pressure bar 60 with associated bolts 62 for clampingly engaging the blade 38 of a fuse. Likewise, the setscrew 56 cooperates with the opening 68 to clampingly engage the cable 20, in a manner similar to that shown in FIG. 2.

A third embodiment of the invention is shown in FIG. 5 wherein a pair of spaced members 78 and 80 are disposed on opposite sides of a fuse blade 82 and in clamping engagement therewith. For that purpose, spaced tightening bolts 84 and 86 extend between juxtaposed flanges 88 and 90, and flanges 92 and 94, respectively. The flanges 88 and 92 are integral parts of the member 78, and the flanges 90 and 94 are integral parts of the member 80. The flange 94 includes an outturned portion 96 by which the assembly of the members 78 and 80 may be attached to a wall of the enclosure 18 by suitable means such as a bolt 98. In other respects, the members 78 and 80 resemble the adapter 16 in that they are provided with similar openings 42 and 44 as well as with corresponding setscrews 56 by which cables 20 may be clampingly engaged in a manner set forth above.

Accordingly, the adapter or connector of the present invention satisfies disadvantages associated with prior art devices, and provides a more economical means of combining fuse clamps and wire or cable terminals into an extruded adapter whereby electrical joints which otherwise serve as sources of overheating are avoided.

It is to be noted that both embodiments of the invention shown in FIGS. 2 and 4 include two spaced parallel portions at least one of which portions, such as flange 76 in FIG. 4, is provided with opening means adapted

to mounting the adapter on a support member.

CROSS-REFERENCE TO RELATED APPLICATION

This invention relates to the invention disclosed in the application of John E. Grad, Ser. No. 228,134, filed Feb. 22, 1972.

What is claimed is:

1. An adapter for connecting an electric cable to a blade-type fuse, the adapter comprising a single unitary metal body having first clamping means for holding an electric cable in electrical contact with the body, the metal body having second clamping means for holding the blade of a blade-type fuse in contact with the body, and the body having at least two spaced parallel portions, one of which portions is provided with opening means for mounting the body on a support member.
2. The adapter of claim 1 in which the first clamping means comprises aperture means for receiving an electric cable.
3. The adapter of claim 2 in which the first clamping means comprises set screw means extending through the body and into the aperture means for clampingly engaging an electric cable in the aperture means.
4. The adapter of claim 1 in which the first clamping means comprises at least one cable-receiving aperture and a set screw threadedly seated in the body and movable into the aperture.
5. The adapter of claim 4 in which the body includes a clamping surface and the second clamping means comprises a bar and bar-mounting bolts for adjustably mounting the bar at varying distances from the clamping surface.
6. The adapter of claim 4 in which the second clamping means comprises a pressure bar, and in which the set screw and pressure bar are spaced longitudinally of the axis of the aperture.
7. The adapter of claim 1 in which the second clamping means comprises pressure bar and means for mounting the bar on the body.
8. The adapter of claim 7 in which the body includes a clamping surface engageable with a blade of a blade-type fuse when the blade is clamped in place between the surface and the bar.
9. The adapter of claim 7 in which the means for mounting the bar comprises at least one bolt threadedly seated in the body.
10. The adapter of claim 9 in which the body includes two cable-receiving apertures and the clamping surface is disposed in a plane substantially parallel to the axes of the apertures.
